COTTON-FEEDER MECHANISM

Application filed September 9, 1927. Serial No. 218,507.

The present invention is concerned with an improved mechanism for feeding cotton to a gin stand, burr extractor, cotton cleaner, boll breaker, or other generally analogous type of machine for operating on cotton.

An object of the invention is to provide a continuous and automatic feed mechanism which will eliminate many of the disadvantages incidental to the use of the intermittent or quasi-intermittent feeds now commonly employed.

Most of the feed mechanisms which are at present utilized, feed cotton either too fast, or not at all; failing to screen as much dirt out of the cotton as could be screened with a continuous and even feed. Rapid feeding of the cotton also, especially in damp weather, tends to cause it to choke in passing through the huller ribs or analogous parts of the mechanism. Such an intermittent feed also fails to permit clean separation of the cotton from the burrs or hulls. In addition, the intermittent feeders required so much pressure to operate them, that a very tight roll is often formed in the roll box, this tight roll causing what is known as gin-cut cotton, a low grade product.

In accordance with the present invention, I have eliminated all of these difficulties by the provision of a feed which is entirely automatic, and with which the speed of the feed rolls is regulated with extreme accuracy by the pressure of the cotton in the roll box without requiring carrying of a tight roll to effect accurate speed regulation of the feed rolls.

Other and more general objects of the invention are to provide a unique feed mechanism of extremely simple practical construction, which will be rugged, durable and efficient in use, and well suited to the requirements of economical manufacture and convenient manual adjustment.

With the above noted and other objects in view, the invention consists in certain novel features of construction and combinations and arrangements of parts, as will be more fully hereinafter set forth and pointed out in the claims. The invention may be more fully understood from the following description

in connection with the accompanying drawings, wherein—

Fig. 1 is a view mainly in side elevation and partly in vertical section showing my improved feed mechanism applied to a cotton gin feeder.

Fig. 2 is an enlarged sectional detail on the line 2—2 of Fig. 1.

It is to be understood at the outset that while I have shown the feed associated with a cotton gin, it is applicable to various other cotton cleaning or handling mechanisms as above suggested, and that the present drawings, while illustrative of one embodiment of the invention, are by no means to be interpreted in a limiting sense.

In the drawings I have used the reference numeral 10 to designate generally a feed mechanism which receives cotton from a belt conveyor or any other suitable apparatus and delivers it to a cleaning or pleating apparatus indicated generally at 11, which in the present instance has been illustrated as a gin. The cotton in bat form having passed through the cleaning mechanism is received in a roll box 12 provided with a hinged pressure plate 13, which is acted upon by the pressure of the cotton roll in the box 12 to automatically regulate the speed of the feeding mechanism 10.

The cotton is passed into the feed mechanism 10 through the conventional feed rolls (not shown), which rolls are actuated by a pair of intermeshing feed roll gears 14 and 15 of equal size. The feed rolls pass the cotton on to the usual spiked feed drum seen in dotted lines at 16, the shaft 17 of this drum carrying the usual driving pulley (not shown) driven as by a belt 18 from any suitable source of power. On the other end of the drum shaft 17 is mounted a friction disc 19 forming part of a variable speed mechanism through which power is transmitted from the drum shaft to the feed roll gears.

This variable speed mechanism includes a second friction disc 20 disposed in parallelism with the disc 19, but spaced therefrom. Disc 20 overlapping the disc 19 to any desired extent is carried by a stub shaft 21 mounted in the frame of the feed mechanism 10.

Power is transmitted from the disc 19 to the disc 20 through a speed changing friction disc 22 disposed at right angles to the planes of the discs 19 and 20 and frictionally contacting with both of said discs. The disc 22 is rotatable on the end of a link 23 slidably mounted in a bearing 24 at one end of the drum shaft 17. Springs 25 and 26 serve to urge the discs 19 and 20 into firm frictional engagement with the speed changing disc 22.

5 A worm 27 carried by the stub shaft 21 actuates a skew gear 28 on a counter shaft 29, the latter carrying a worm 30 adjacent its upper end which drives the feed roll gear 15. 15 Particular attention is called to the special arrangement of worm 27 and skew gear 28, the threading of the worm being such, that, it automatically tends to pull the disc 20 in against the friction disc 22 as an incident of 20 driving the skew gear. Various modifications of such an arrangement might of course be worked out, but it is essential that the threading of the worm be such that the disc 20 is urged against the friction disc 22 instead of away from it in the ordinary course 25 of transmitting the power through the worm 27.

It will be seen that sliding the shaft 23 in its bearing 24 will act to vary the speed ratio 30 between the discs 19 and 20; movement of the disc 22 to the left in Fig. 2 reducing the speed of gear 20, while movement to the right increases it, the speed of the disc 19 being constant.

35 Means is provided for operatively connecting the pressure plate 13 of the roll box to the sliding shaft 23 of the speed disc 22, so that when the pressure plate 13 is bulged out by a roll of cotton in the box, shaft 23 will be 40 drawn to the left and reduce the speed of the feed roll gears 14 and 15.

This mechanism includes a rod 31 carried by the pressure plate 13, and pivotally connected to the end of the shaft 23. Rod 31 45 preferably carries a right angularly disposed arm 32 along which a counter weight 33 is adjustable to regulate the pressure on the plate 12. Means is also provided for manually sliding the rod 31 to adjust the initial 50 speed of the drive. Such means includes a lever 34 pivoted as at 35 on the cotton trough 36 and cooperating with a toothed sector 37. Instead of the usual dog to lock the lever in place, I have provided a worm 38 normally 55 engaged with the teeth of the sector and capable of being withdrawn from engagement by a small lever handle 39. The worm may be rotated to effect minute adjustments by turning a handle 40 on the upper end of a 60 shaft 41 mounted on the lever 34. The lower end of the shaft 41 and the end of the shaft which carries the worm 38 are provided with intermeshing bevelled gears 42, so that rotation of the handle 40 permits minute or 65 microscopic adjustments of the lever about

its pivot 35, this lever being connected as at 43 to the rod 31 so that lever movement is imparted directly to the rod. When the machine is operating automatically, the handle 39 is lifted upwardly to disengage the worm 38 and the worm retained out of engagement by slipping a retaining hook or ring 44 over the lever 39.

70 Obviously various changes and alterations 75 might be made in the general form and arrangement of the parts described without departing from the invention. Hence I do not wish to limit myself to the details set forth, but shall consider myself at liberty to make such changes and alterations as fairly fall within the spirit and scope of the appended claims.

80 I claim:

85 1. The combination with a cotton handling machine including a roll box, of a continuous and automatic feed mechanism including a pair of meshing feed roll gears, a feed drum, a variable speed reduction mechanism driven from the drum, gearing between the speed reduction mechanism and one of the feed roll gears, a pressure plate constituting part of the roll box, and operative connections between the variable speed mechanism and the pressure plate, whereby to automatically vary the speed of the feed roll gears incident to the 90 movement of the pressure plate.

95 2. The combination with a cotton handling machine of the class described including a roll box having a pressure plate, of a continuous and automatic feed mechanism including a 100 pair of feed roll gears, a feed drum, a variable speed reduction mechanism driven from the drum, means for operating the feed roll gears from the speed reduction mechanism, a pressure plate constituting part of the roll box, and operative connections between the variable speed mechanism and the pressure plate, said connections including a 105 slidable shaft actuated by movement of the pressure plate and carrying the speed change element of the reduction mechanism, movement of the pressure plate serving to automatically vary the speed of the variable speed mechanism and the feed roll gears.

110 3. The combination with a cotton handling machine of the class described including a roll box, of a continuous and automatic feed mechanism including a pair of feed roll gears, a feed drum, a variable speed reduction mechanism for driving the feed roll gears from the drum, a pressure plate constituting part of the roll box, operative connections between the variable speed mechanism and the pressure plate, and means for manually and minutely setting the speed varying mechanism, said mechanism including a rack and a worm engaging the rack.

115 4. The combination with a cotton handling machine of the class described including a roll box, of a continuous and automatic feed

mechanism including a pair of feed roll gears, a feed drum, a variable speed reduction mechanism for driving the feed roll gears from the drum, a pressure plate constituting part of the roll box, operative connections between the variable speed mechanism and the pressure plate, and means for manually setting the speed varying mechanism, said manual setting means including an associated lever and segment rack for making wide adjustments, and a worm carried by the lever engageable with the rack and serving as a locking dog for the lever.

5. The combination with a cotton handling machine of the class described including a roll box, of a continuous and automatic feed mechanism including a pair of feed roll gears, a feed drum, a variable speed reduction mechanism for driving the feed roll gears from the drum, a pressure plate constituting part of the roll box, operative connections between the variable speed mechanism and the pressure plate, means for manually setting the speed varying mechanism, said manual setting means including an associated lever and segment rack for making wide adjustments, a worm carried by the lever engageable with the rack and serving as a locking dog for the lever, and means for rotating the worm to feed the lever along the rack.

6. The combination with a cotton handling machine of the class described including a roll box, of a continuous and automatic feed mechanism including a pair of feed roll gears, a feed drum, a variable speed reduction mechanism for driving the feed roll gears from the drum, a pressure plate constituting part of the roll box, operative connections between the variable speed mechanism and the pressure plate, means for manually setting the speed varying mechanism, said manual setting means including an associated lever and segment rack for making wide adjustments, a worm carried by the lever engageable with the rack and serving as a locking dog for the lever, means for rotating the worm to feed the lever along the rack, and means for disengaging the worm from the rack and retaining it in disengaged position to permit automatic control of the feed roll speed from the roll box pressure plate.

7. The combination with a cotton handling machine of the class described including a roll box having a pressure plate, of a continuous and automatic feed mechanism including a pair of feed roll gears, a feed drum, a variable speed reduction mechanism for driving the feed roll gears from the drum, a pressure plate constituting part of the roll box, and operative connections between the variable speed mechanism and the pressure plate, said mechanism including a friction disc on the drum shaft, a second spaced parallel disc on a stub shaft, and a right angularly disposed, axially shiftable friction disc connected with

the pressure plate of the roll box and driving the stub shaft disc from the drum shaft disc.

8. In a continuous and automatic cotton feeding mechanism, a roll box having a pressure plate, a pair of meshing feed roll gears, a feed drum, a friction disc on the shaft of said drum, a stub shaft having a worm thereon, a friction disc on the stub shaft parallel with and spaced from the first disc, a right angularly disposed friction disc between and engaging the said discs, a slidable shaft upon which the angularly disposed friction disk is mounted, means for sliding and rocking said shaft, means connecting the said shaft with the pressure plate of the roll box, and a vertical shaft having on its upper end a worm meshing with one of the feed roll gears and on its lower end a gear meshing with the worm of the stub shaft.

9. In combination, a cotton handling machine having meshing feed roll gears, and a roll box having a pressure plate, a variable speed mechanism operatively connected with one of the gears, and means operable incident to movement of the pressure plate for varying the speed of the variable speed mechanism and thereby control the speed of the feed roll gears.

Signed at Clarendon in the county of Donley and State of Texas this 15th day of August A. D. 1927.
